DESIGN.

C. F. HUBBS,

PAPER ROLL HOLDER.

APPLICATION FILED APR. 8, 1915.

47,518.

Patented June 29, 1915.

Inventor:

Charles F. Hubbs

By his Atty's:

Philip Sawyer Rice Kennedy

UNITED STATES PATENT OFFICE.

CHARLES F. HUBBS, OF NEW YORK, N. Y.

DESIGN FOR A PAPER-ROLL HOLDER.

47,518.

Specification for Design.

Patented June 29, 1915.

Application filed April 8, 1915. Serial No. 20,057. Term of patent 14 years.

To all whom it may concern:

Be it known that I, CHARLES F. HUBBS, a citizen of the United States, residing at New York city, borough of Brooklyn, county of Kings, State of New York, have invented a new, original, and ornamental Design for a Paper-Roll Holder, of which the following is a specification, reference being had to the accompanying drawing, forming part thereof.

The figure is a perspective view of a paper roll holder showing the new design.

I claim:

The ornamental design for a paper roll holder, as shown.

CHARLES F. HUBBS.

Witnesses:

CHARLES P. WHITE,
W. A. UNDERHILL.
